UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

FILLING-REPLENISHING MECHANISM FOR LOOMS.

Application filed July 28, 1923. Serial No. 654,355.

To all whom it may concern:

Be it known that I, ALONZO E. RHOADES, a citizen of the United States, residing at Hopedale, in the county of Worcester and 5 State of Massachusetts, have invented an Improvement in Filling-Replenishing Mechanisms for Looms, of which the following description, in connection with the accompanying drawings, is a specification, like 10 characters on the drawings representing like parts.

This invention relates to filling replenishing mechanisms for looms whereby the filling is replenished from time to time. In a 15 prior application filed by Alonzo E. Rhoades, Serial No. 641,480, May 25, 1923, a feeler mechanism was shown, described and claimed wherein the feeler was retained in a frontward or inactive position for periods of time and was released for short periods to perform its feeling function, the 20 purpose being in said application to prevent injury to the yarn in the shuttle incident to contact therewith by the feeler on each detecting beat. The present invention is a 25 further development of the feeler mechanism of the prior application and has for its object to provide a feeler mechanism of simplified construction and which will be 30 effective in operation to intermittently engage the filling for periods of activity of the feeler and hold the feeler from cooperative 35 relation with the filling during periods of inactivity.

The various features of the invention and new combination of parts will best be made 40 clear from the following description and the accompanying drawings of one good form thereof, and the true scope of the invention will be defined by the claims.

In the drawings:

Fig. 1 is a perspective view at one side of the loom and equipped with a feeler mechanism embodying the present invention; 45 Fig. 2 is an enlarged detail showing the actuator operated by the take-up mechanism and a part of the controller;

Fig. 3 is an enlarged detail in side elevation, showing the detent withdrawn to free 50 the feeler to the performance of its feeling function;

Fig. 4 is a view similar to that of Fig. 3 but showing the detent in an intermediate 55 position ready to engage the projection on the feeler should the feeler be moved front-

wardly by a working supply of filling in the shuttle;

Fig. 5 is a view similar to that of Figs. 3 and 4 but showing the detent in engagement with the projection on the feeler; 60

Fig. 6 is a similar view in detail showing the detent as having been thrust towards the plane of action of the feeler from the position of Fig. 5 to withdraw the feeler frontwardly out of cooperative relation with 65 the filling;

Fig. 7 is a perspective view of the feeler mechanism showing the feeler in its frontwardly withdrawn position which it occupies during normal operation of weaving; 70

Fig. 8 is a detailed side elevation partly in section, showing the feeler in its finally released position for effecting a change of filling when that in the shuttle is substantially 75 exhausted.

It has not been deemed necessary herein to illustrate and describe the filling replenishing mechanism which is set in operation by movement of the feeler to call the change, 80 because such mechanism is now well understood and the details thereof form no essential part of the present invention.

In the feeler mechanism shown, the feeler is of the inclined type and may be substantially the same as the feeler shown and described in the patent to Stimpson, No. 1,309,226, July 8, 1919, and while the advantages of the present invention are made manifest in connection with such type of 90 inclined feeler, the invention is not restricted thereto, as the feeler may be of any usual character.

Extending between the loom sides 1 is the breast beam 2 having secured thereto at each side of the loom a bracket 3 provided with bearings 4 in which is mounted the transverse or rock shaft 5 of usual construction, and normally held in the position indicated in Fig. 1 by a spring, as usual, but not herein shown. Secured to and extending upwardly from the rock shaft 5 is an arm 6 to which is pivoted at 7 the arm 8, the rear end portion of which has connected thereto the member 9 by means of a pivot 10. Connected to or formed as part of the cam follower is an operating member 11 which at times determined by the feeler engages the member 9 and by its forward movement turns the rock shaft 5 to call for 110

replenishment of filling. Extending from the member 9 is a finger 12 which overlies the horizontal arm of a bell crank lever 13 mounted on a support 14 secured to the loom frame. The vertical arm of the bell crank 13, in the present instance, is connected to an actuator 15 whose other end is connected at 16 to a slide 17 mounted in suitable guides 18 at the rear of the feeler stand 19.

10 The feeler stand 19 is shown as adjustably secured to the loom frame, or bracket attached thereto, by means of a bolt 20 which passes through a slot 21 in the feeler stand. Mounted on the feeler stand is the 15 feeler 22 which passes through a slot in the slide 17 and has its forwardly extending stem 23 supported in a swivel block 24 mounted at the front of the feeler stand. Between the block 24 and the bridge 25 secured to the feeler is a spring 26 normally tending to move the feeler into its rearward feeling position. The parts so far described and their operation in detecting substantial exhaustion of filling and effecting replenishment thereof are or may be substantially the same as the corresponding parts shown and described in the Stimpson patent hereinbefore mentioned.

10 The lay 27 has the usual shuttle box 28 the front wall of which has an opening 29 which registers with a corresponding opening 30 in the front wall of the shuttle 31 when the latter is in the detecting box, the construction being such that on the detecting 35 beatup of the lay the rear end of the feeler may enter the shuttle and detect the condition of the filling therein, and on detection of substantial exhaustion of filling effect replenishment thereof.

40 From the construction so far described it will be apparent that should the feeler 22 detect a working supply of filling in the shuttle on a detecting beat, it will be moved forwardly and held from its "side swipe" 45 movement longitudinally of the shuttle by engagement with the filling, but should the filling be substantially exhausted on a detecting beat the feeler will not be held from its "side swipe" movement by the filling and 50 will move longitudinally of the shuttle to thereby call the change.

55 The constantly recurring contact of the feeler with the filling is liable to cause injury to the latter, especially where the filling is of fine character or of material such as silk or the like, and one of the purposes of the present invention is to hold the feeler in a forward inactive position out of cooperation with the filling on detecting beats 60 during a period of inactivity, and to release the feeler at intervals that it may perform its detecting function and call for a change of filling should that in the shuttle be substantially exhausted.

In accordance with the present invention 65 the feeler 22 is provided with a projection or tooth 32 at its front portion which is adapted to be engaged by a detent to hold the feeler in its forward retracted or inoperative position for periods of inactivity, 70 and the detent is mounted to be withdrawn from engagement with the projection from time to time to permit the feeler to return to its feeling position and detect the condition of the filling in the shuttle. 75

Mounted at the front of the feeler mechanism and preferably secured to the feeler stand is a bracket 33, Fig. 1, which may be conveniently secured to the feeler stand by a bolt 34. The bracket 33 carries a guide 80 for a detent carrier or slide 35, and in the present instance the guide is shown as a casting 36 having a cover plate 37 secured thereto by screws 38, and containing within it the slide 35 which is capable of movement 85 towards and from the plane of action of the feeler.

Pivoted connected to the slide 35 at 39 is a pawl or detent 40, the feeler engaging end 41 of which extends forwardly. 90

The detent 40 is normally under the influence of a spring 42 interposed between it and the carrier or slide 35. In the present instance of the invention the spring 42 is contained within a recess 43 in the slide or carrier 35 and bears at its upper end in a recess 44 formed in the lower surface of the detent, the construction being such that the energy of the spring is exerted in an upward direction to throw the engaging end 41 of the detent into position to engage behind the projection 32 of the feeler when the latter is moved forwardly by a working supply of filling in the shuttle. The detent 40 is limited in its upward swinging movement about its pivotal support 39 by a stop 45 which is adapted to engage the upper surface of the slide or carrier 35 when the detent is swung about its pivotal support by the spring 42. Slots 46 may be made in the casing 36 into which the detent may pass when it is lowered. 110

115 The carrier or slide 35 extends below the guide or casing 36 and at its lower end is connected to a controller 47, the lower end of which is connected at 48 to one arm 49 of a lever pivoted at 50 to a bracket 51 which may be conveniently secured to the flange 52 of the side frame 1 of the loom. The arm 49 of the lever is normally under the influence of a spring 53 tending to raise the arm 49 and perform move the slide or carrier 35 on which the detent is mounted in an upward direction or towards the plane of operation of the feeler. In the present instance the spring 53 is contained within a pocket 54 secured to the bracket 51 and its upper end bears upon a lug 55 connected to 120 125

the arm 49 of the lever. The spring for normally moving the slide through the controller may, of course, be variously contrived, but that shown and described presents a good practical form of this feature of the invention.

Looms as at present constructed are provided with a take-up mechanism for taking up the cloth as it is woven. There are various forms of take-up mechanisms, any one of which may be appropriately employed, but in the present instance the take-up mechanism comprises a pick wheel 56 which is stepped along from a going part of the loom, as usual. Between the pick wheel 56 and the take-up or sand roll is interposed a train of transmission mechanism which may be of usual construction. In the present instance the train of mechanism comprises the toothed wheels or gears 57, 58, 59 and 60, Fig. 1, the last of which is in operative relation with the sand or take-up roll, the construction being such that during the operation of the loom, the pick wheel is stepped along and the cloth is taken up as it is woven.

The pick wheel, in the present instance of the invention, is provided with spokes 61, one or more of which carry an actuator 62 for operating the slide controller at intervals. The actuator 62 is provided with a trip portion 63 and a dwell portion 64 which act upon the arm 65 extending from the pivotal support 50 and connected to the arm 49.

When during the weaving operation the trip portion 63 of the actuator engages the arm 65 connected to the slide controller, the slide and detent are bodily lowered to free the feeler and permit it to perform its feeling function, as indicated in Figs. 1 and 3, and when the dwell portion 64 of the actuator engages the arm 65 the slide and detent are permitted to move upwardly or towards the plane of operation of the feeler into an intermediate position, as indicated in Fig. 4, at which time the end 41 of the detent is in position to engage the projection 32 of the feeler should the latter be moved forwardly by a working supply of filling on a detecting beat, as indicated in Fig. 5.

When the dwell portion of the actuator moves out of engagement with the arm 65, the slide and detent are given a further upward movement or thrust, and since the end 41 of the detent is then engaged with the projection 32 of the feeler, the detent is caused to move about its pivotal support 39 in a forward direction to withdraw the feeler forwardly away from cooperative relation with the filling on a detecting beat so that during subsequent detecting beats the feeler will not contact with the filling, and the parts assume the position as indicated in Fig. 7 until the trip portion 63 of

the actuator again acts through the controller to bodily move the slide or carrier and detent downwardly or away from the plane of action of the feeler.

Since the final upward thrust upon the detent is utilized in accordance with the present invention to withdraw the feeler forwardly out of cooperative relation with the filling, the importance of the dwell in the actuator will be apparent.

Thus during normal weaving operations with a working supply of filling in the shuttle the feeler is held forwardly out of contact with the filling on detecting beats for periods of inactivity, which may be longer or shorter as dictated by the actuator, and at intervals the feeler is freed to the performance of its feeling function during relatively shorter periods of activity and is then moved forwardly by a thrust upon the detent when the latter is engaged with the feeler.

Should the filling be substantially exhausted, however, on a detecting beat, it will not be moved forwardly sufficiently far to engage the projection 32 with the end 41 of the detent, as indicated in Fig. 8, and the feeler will continue to perform its feeling function until, when the critical period is reached, the feeler will call for a change of filling.

The actuator 62 for operating the detent, as hereinbefore described, is shown in the present instance as a lug which may be secured to the pick wheel or some other part of the take-up mechanism by a bolt 66 and nut 67, but obviously the form of the actuator may be varied, the essentials in this respect being that the actuator will first trip the detent from the feeler and then maintain the detent in an intermediate position for a time until the feeler is moved forwardly by the filling and is engaged by the detent, whereupon the dwell of the actuator may pass out of engagement with the arm 65 and the detent given its upward thrust under the impulse of the spring 53 to withdraw the feeler from cooperative relation with the filling.

What is claimed is:

1. In a feeler mechanism for looms, the combination of a feeler to detect substantial exhaustion of the filling and thereupon initiate replenishment of filling, a pivoted detent for holding the feeler in forward position for periods of inactivity, and means for exerting a thrust upon the detent when engaged with the feeler to cause the detent to turn upon its fulcrum and remove the feeler forwardly from cooperative relation with the filling on detecting beats.

2. In a feeler mechanism for looms, the combination of a feeler to detect substantial exhaustion of the filling and thereupon

initiate replenishment of filling, a projection carried by the feeler, a pivoted detent for engaging the projection to hold the feeler in frontward position for periods of inactivity, means for exerting a thrust upon the detent when engaged with said projection to cause the detent to turn upon its pivotal mounting and move the feeler from cooperative relation with the filling on detecting beats, and means for tripping the detent to free the feeler for periods of activity.

3. In a feeler mechanism for looms, the combination of a feeler to detect substantial exhaustion of the filling and thereupon initiate replenishment of filling, a projection carried by the feeler, a pivoted detent for engaging the projection to hold the feeler in frontward position for periods of inactivity, means for exerting a thrust upon the detent when engaged with said projection to cause the detent to turn upon its pivotal mounting and move the feeler from cooperative relation with the filling on detecting beats, and means actuated from the take-up mechanism for tripping the detent to free the feeler for periods of activity.

4. In a feeler mechanism for looms, the combination of a feeler to detect substantial exhaustion of the filling in the shuttle and thereupon initiate replenishment of filling, a projection carried by the feeler, a slide mounted for movement towards and from the plane of action of the feeler, a detent mounted upon the slide to engage said projection and hold the feeler frontward for periods of inactivity, a slide controller for moving the slide towards the plane of action of the feeler to exert a thrust upon the detent when engaged with the projection on the feeler and cause the detent to withdraw and hold the feeler from cooperative relation with the filling on detecting beats.

5. In a feeler mechanism for looms, the combination of a feeler to detect substantial exhaustion of the filling in the shuttle and thereupon initiate replenishment of filling, a projection carried by the feeler, a slide mounted for movement towards and from the plane of action of the feeler, a detent mounted upon the slide to engage said projection and hold the feeler frontward for periods of inactivity, a slide controller for moving the slide towards the plane of action of the feeler to exert a thrust upon the detent when engaged with the projection on the feeler and cause the detent to withdraw and hold the feeler from cooperative relation with the filling on detecting beats, and means actuated from the take-up for withdrawing the slide and detent to free the feeler for periods of activity.

6. In a feeler mechanism for looms, the

combination of a feeler to detect substantial exhaustion of filling and thereupon effect replenishment of filling, a pivoted detent mounted for bodily movement towards and from the plane of action of the feeler and having its free end extending frontwardly to engage the feeler, means for moving the detent bodily towards the feeler when engaged therewith to cause the detent to withdraw the feeler and hold it frontwardly from cooperative relation with the filling during periods of inactivity, and means for bodily moving the detent from the feeler to free it for periods of activity.

7. In a feeler mechanism for looms, the combination of a feeler to detect substantial exhaustion of the filling and thereupon effect replenishment of filling, a pivoted detent mounted for bodily movement towards and from the plane of action of the feeler and having its free end extending frontwardly to engage the feeler, means for moving the detent bodily towards the feeler when engaged therewith to cause the detent to withdraw the feeler and hold it frontwardly from cooperative relation with the filling during periods of inactivity, and means actuated by the take-up mechanism for bodily moving the detent from the feeler to free it for periods of activity.

8. In a feeler mechanism for looms, the combination of a feeler to detect substantial exhaustion of the filling and having a projection, a slide mounted for movement towards and from the plane of action of the feeler, a pivoted detent mounted on the slide and having its free end extending frontwardly to engage the projection, a slide controller normally acting upon the slide to move the detent bodily towards the feeler and when engaged with the projection to hold the feeler from cooperative relation with the filling, and means acting through the slide controller for freeing the feeler from the detent for periods of activity.

9. In a loom, the combination of a take-up mechanism, a feeler to detect substantial exhaustion of the filling, a detent for holding the feeler in a frontward position for periods of inactivity, a controller for controlling the detent, and an actuator on the take-up mechanism comprising a trip and a dwell portion acting through the controller to trip the detent and free the feeler and cause the detent to dwell in an intermediate position for engagement with the feeler should it be moved frontwardly by a working supply of filling in the shuttle on a detecting beat.

10. In a loom, the combination of a take-up mechanism, a feeler, a detent for holding the feeler during periods of inactivity, a controller for the detent, and an actuator for the controller mounted on the take-up mechanism and comprising a trip and a dwell portion which act successively through

the controller to free the feeler and then cause the detent to dwell in an intermediate position to reengage the feeler, and means acting upon the controller to cause the detent to withdraw the feeler from cooperative relation with the filling when the controller is freed from the actuator.

11. In a feeler mechanism for looms, the combination of a feeler, a slide mounted for movement towards and from the plane of the feeler movement, a detent pivotally mounted upon the slide and having a frontwardly extending feeler engaging end, a controller for the slide, a spring normally tending to move the slide towards the plane of the feeler movement, take-up mechanism, a controller actuator having a trip and dwell portion and mounted on a member of the take-up mechanism.
12. In an intermittent feeler mechanism for looms, the combination of a feeler having periods of activity and inactivity during weaving with the same supply of filling in the shuttle, means for holding the feeler

in a position beyond the reach of the filling in the shuttle that it may not contact with the filling on detecting beats during its periods of activity, and a dwell device for permitting the holding means to assume an intermediate position during a period of activity of the feeler until the lay has made a detecting beat.

13. In an intermittent feeler mechanism for looms, the combination of a feeler having periods of activity and inactivity during weaving with the same supply of filling in the shuttle, means for moving the feeler to a position beyond the reach of the filling that it may not contact with the filling during its periods of inactivity, and a dwell device for permitting said means to assume an intermediate position during a period of activity until the feeler has been moved frontwardly by the filling on a detecting beat.

In testimony whereof, I have signed my name to this specification.

ALONZO E. RHOADES.
